UNITED STATES PATENT OFFICE.

GEORGE E. CORBETT, OF BROOKLYN, NEW YORK, ASSIGNOR TO J. F. NEWMAN, INC.,
OF NEW YORK, N. Y., A CORPORATION OF NEW YORK.

DESIGN FOR A BADGE.

Application filed September 30, 1922. Serial No. 3,857. Term of patent 7 years.

To all whom it may concern:

Be it known that I, GEORGE E. CORBETT, a citizen of the United States, residing at New York, borough of Brooklyn, in the county of Kings and State of New York, have invented a new, original, and ornamental Design for a Badge, of which the following is a specification, reference being had to the accompanying drawing, forming part thereof.

Fig. 1 is a front view of such a badge and Fig. 2 a side view thereof.

I claim:

The ornamental design for a badge as shown.

GEORGE E. CORBETT.
